UNITED STATES PATENT OFFICE.

ERHARD ALLEN, OF DAYTON, OHIO, ASSIGNOR TO THE DAYTON DISPLAY FIXTURE COMPANY, OF DAYTON, OHIO, A CORPORATION OF OHIO.

DESIGN FOR A DISPLAY-RACK.

59,053.

Specification for Design. Patented Sept. 20, 1921.

Application filed January 31, 1921. Serial No. 441,483. Term of patent 14 years.

To all whom it may concern:

Be it known that I, ERHARD ALLEN, a citizen of the United States, residing at Dayton, in the county of Montgomery and State of Ohio, have invented a new, original, and ornamental Design for Display-Racks, of which the following is a specification, reference being had to the accompanying drawing, forming part hereof.

In the drawings, the figure is a perspective view of a box rack showing my new design.

I claim:

The ornamental design for a display rack as shown.

ERHARD ALLEN.
